**FLUID DISPLACEMENT LIGHT BEAM SELECTION
AND POSITIONING APPARATUS**
Joseph T. McNaney, 8548 Boulder Drive, La Mesa, Calif.
Filed May 11, 1962, Ser. No. 194,087
10 Claims. (Cl. 340—347)

This invention relates to an improvement in means designed to convert binary code related input functions to light beam selection, selection-compensation, and light beam recording-position functions through the use of hydraulic fluid displacement techniques.

The present invention utilizes a hydraulic fluid as a means of linking together a system of binary code related fluid displacement members with fluid displacement-responsive members for the establishment of light beam selection, selection-compensation, and recording-position functions necessary for displaying or making a record of message characters in response to coded input information. The fluid intermediate the various members is contained within a hermetically sealed envelopment of which these members are a part, therefore, upon the application of an input function to any one or a combination of displacement members the fluid serves as a means of totalizing and imparting an output function to one or more displacement-responsive members. Light reflector means is associated with the displacement-responsive members for providing the light beam selection, selection-compensation, and recording-position functions in accordance with the requirements of the coded input commands.

An object of this invention is to provide a light beam selection and positioning apparatus of the type referred to which is exceptionally accurate, capable of high speed operation, dependable over long periods of time, and relatively simple in construction.

Numerous other objects, of course, will appear hereinafter as a description of the invention proceeds.

The novel features that are considered characteristic of this invention are set forth with particularity in the appended claims. The invention itself, both as to its organization, and method of operation, as well as additional objects and advantages, will best be understood from the following description when read in connection with the accompanying drawings in which:

FIGURE 1 is a schematic diagram of a hydraulic fluid displacement mechanism for converting binary code related input functions to light beam selection functions, selection-compensation functions, and light beam recording-position functions;

FIGURE 2 shows a detail of a fluid displacement means used in the FIGURE 1 embodiment of the invention;

FIGURE 3 shows a detail of a fluid displacement-responsive member and light reflector means used in the FIGURE 1 embodiment;

FIGURE 4 shows a detail of another fluid displacement-responsive member and light reflector means used in the FIGURE 1 embodiment; and

FIGURE 5 represents an example of a type of beam forming member capable of being used in the invention.

Referring now to FIGURE 1, the fluid displacement light beam selection and positioning apparatus is shown schematically to include a first envelopment 10 and a second envelopment 11, each being represented by a cross section of a complete envelopment; and each envelopment shown to comprise a main body 12 of rigid construction, a plurality of fluid displacement diaphragms 14, and a fluid displacement-responsive diaphragm 16. The space 18 within each envelopment 10 and 11 is filled with a hydraulic fluid, such as oil, or other forms of hydraulic fluid, to essentially link the

2

various diaphragms of each envelopment together whereby movements of one or more of the displacement diaphragms 14 will be imparted to a displacement-responsive diaphragm 16. All of the fluid displacement diaphragms 14, or flexible members 14, are capable of being flexed in a direction away from the fluid in space 18, or, against the fluid. When a diaphragm 14 is made to move in a direction away from the fluid the atmospheric pressure surrounding the envelopments will allow the displacement-responsive diaphragm 16, or flexible member 16, and the fluid to be displaced in the direction of the diaphragm 14 movement. Under these circumstances the flexible member 16 will move with the fluid in the direction of arrow 20. When a diaphragm 14 is allowed to return in a direction against the fluid the flexible member 16, of course, will move with the fluid displacement in the direction of arrow 22.

Each of the diaphragms 14 are provided with a centrally located shaft-like member 24 which is supported by the main body 12, and against which a diaphragm 14 is made to rest under its own spring tension. The primary function of the member 24 is to serve as a reference bearing for the diaphragm 14. On the opposite side of each diaphragm 14 there is a solenoid actuator 26 having a pole piece 28 which is supported a predetermined distance from the diaphragm 14. In FIGURE 2 a detail of this fluid displacement means is shown. When, for example, the solenoid actuator 26 is in a de-energized condition the diaphragm 14 will be in the position as shown, resting against the member 24, and a predetermined distance from the one end 30 of the pole piece 28. When the solenoid actuator 26 is energized, however, the diaphragm 14, being of magnetically permeable material, will be flexibly dished in the direction of the pole piece 28 until it comes to rest against the end 30, as indicated by a dotted line position 32 of the diaphragm 14. Although the member 24 has a primary function of serving as a reference bearing against which a diaphragm 14 will come to rest, the member 24 may be of magnetized material and thereby force the diaphragm 14 to be magnetically returned thereto when a solenoid actuator 26 is returned to a de-energized condition.

The fluid displacement-responsive member 16, of the first envelopment 10, is again shown in FIGURE 4, and is designed to receive a mechanical displacement about an axis 34 adjacent one end 36 of the member 16. A bellows-like partition 38 is secured to the outside edges of the member 16 and the main body 12 to satisfy the hermetic seal requirements of the invention, in addition to it allowing an opposite end 40 of the member 16 to respond to fluid displacements. Light reflector means 42, illustrated as being in the form of a mirror 42, is attached to the outside surface 44 of the member 16.

The fluid displacement-responsive member 16a, of the second envelopment 11, is again shown in FIGURE 3, and is designed to receive a mechanical displacement about an axis 35 adjacent one end 37 of the member 16a. A bellows-like partition 39 is secured to the outside edges of the member 16a and the main body 12 to satisfy the hermetic seal requirements of the invention, in addition to its allowing an opposite end 41 of the member 16a to respond to fluid displacements. Light reflector means 43, illustrated as being in the form of a mirror 43, is attached to the outside surface 45 of the member 16a.

The solenoid actuators 26 will be energized by means of electrical currents connected selectively to a system of input terminals 51, 52, 53 and 61, 62, 63, under the control of first and second sets of binary code information. A first set of binary code information will be used in controlling currents to actuators 26a 26b, 26c, of the first envelopment 10 and the second envelopment 11, and a

second set of binary code information will be used in controlling currents to actuators 26x, 26y, 26z, of the second envelopment 11. Furthermore, in response to the first set of binary code information input functions may be applied to predetermined fluid displacement means of the first envelopment 10 and the second envelopment 11, and in response to the second set of binary code information input functions may be applied to predetermined fluid displacement means of the second envelopment 11. The resultant fluid displacements of the first and second envelopments will provide first and second decimalized functions which will be imparted to the member 16 and the member 16a of the first envelopment 10 and the second envelopment 11, respectively, for deriving therefrom light beam selection and light beam recording-position functions.

To illustrate at least one means of utilizing these functions the light reflector means 42 of the first envelopment 10 and the light reflector means 43 of the second envelopment 11 have been arranged in a predetermined manner for receiving light beams from a source 54 and a beam forming member 56, and for controlling the selection and positioning of the light beams for display or recording on a beam receiving means 58. A lens system has been provided for imaging the illuminated matrix 56 on the beam receiving means 58. The matrix 56, or beam forming member 56, is represented in FIGURE 5 as having a series of light transparent areas in the form of letters, abcdefgh. The location of the letters in the matrix 56 coincide, respectively, with the identified decimalized positions, 0 1 2 3 4 5 6 7.

An examination of the invention in conjunction with light beams available in the matrix 56 and the receiving means 58 which has established thereon the decimalized recording positions, 0 1 2 3 4 5 6 7, will be helpful in obtaining a further understanding of how the invention is able to convert binary code related input functions to light beam selection, selection-compensation, and light beam recording-positioning functions, and also how the latter three inter-related functions may be utilized in a binary code to message character recorder.

Light beams in the forms of letters a through h, from the matrix 56, are directed through the lens 60 and onto the reflecting surface of the mirror 42, and reflected therefrom in the direction of the mirror 43. The reflecting surface dimensions of the mirror 43 are designed to be just slightly greater than the height and width of the largest letter to be received from the mirror 42. Since all of the letters being reflected from the mirror 42 are made to follow a course whereby the optical axes of the individual beams are parallel to one another, the center-to-center spacing of the beams and the surface dimensions of the mirror 43 will permit the mirror 43 to function as a limiting aperture, receiving and reflecting but one letter shaped beam at a time.

Under the conditions of a 000 code controlled input to the terminals 51, 52, 53, the letter a-shaped beam will follow optical paths 65 and 66, and the last letter h-shaped beam from the matrix 56 will follow optical paths 67 and 68. Since only the a-shaped beam from the matrix will be on the path which will direct it to the mirror 43, this will then be the only beam to be reflected by the mirror 43. Under the conditions of a 000 code controlled input to the terminals 61, 62, 63, the a-shaped beam will be reflected along an optical path 69, and to a position "0" on the receiving means 58. If, for example, the input codes 001, 010, 100 are applied to the terminals 61, 62, 63, the a-shaped beam will be reflected along an optical path 70, and to a "7" position on the receiving means 58. The other available code combinations capable of being applied to the terminals 61, 62, 63 will allow the a-shaped beam to be reflected along the remaining optical paths intermediate the paths 69 and 70, and to positions 1 through 6 on the receiving means 58, intermediate the "0" and "7" positions.

When, for example, the codes 001, 010, 100 are being applied to the terminals 51, 52, 53, the fluid displacement means under the control of the solenoid actuators 26a, 26b, 26c, of the first envelopment 10, will impart a displacement in the direction of arrow 20 to the member 16, and, the fluid displacement means under the control of the solenoid actuators 26a, 26b, 26c, of the second envelopment 11, will impart a displacement in the direction of arrow 20 to the member 16a. Under these conditions the displacements imparted to members 16 and 16a will be equal, in each case, to binary numeral summations 111, which will permit the letter a-shaped beam to follow the optical paths 65 and 72, while the letter h-shaped beam is following the optical paths 67, 74, 69, assuming of course that a 000 code controlled input exists on the terminals 61, 62, 63.

The optical path 69 from the mirror 43 to the receiving means 58 may be referred to as a zero reference path since all recorder-position functions derived from binary code related input functions will be dependent upon the fact that such a reference path exists. Recording-positioning functions in relation to this zero reference path, therefore, will be proportional to the binary code related input functions being applied to the fluid displacement means under the control of the solenoid actuators 26x, 26y, 26z, of the second envelopment 11.

The optical path 66 from the mirror 42 to the mirror 43, followed by the a-shaped beam, under 000 code input conditions to the terminals 51, 52, 53, will be extended along the optical path 69 by reason of the angular position of the mirror 43 in relation to the paths 66 and 69. And the angular position of the reflecting surface of the mirror 43 in relation to the optical path 69 is a function of light beam selection functions imparted to the reflecting surface of the mirror 42. Therefore, in order to effect the extension of the h-shaped beam, along the optical path 74, along the optical path 69 it will be necessary to derive a selection-compensation function from the binary code related input functions, simultaneously with the light beam selection function, which will result in a displacement of the reflecting surface of the mirror 43. Without the introduction of a selection-compensation function only the a-shaped beam, upon selection, would be permitted to follow the optical path 69. The h-shaped beam, for example, would follow a path 75 somewhat displaced from the zero reference path 69, unless a selection-compensation function were introduced. Although the other letter shaped beams, b through g, would be less divergent in relation to the zero reference path 69 upon selection of any one of them, without selection-compensation none of these beams would be able to follow the zero reference path 69.

In order to relate the fluid displacement functions to a set of binary code related information, the invention is designed to make use of the diaphragm 14 travel distance between the shaft-like member 24 and pole piece 28, in combination with the displaceable area of the diaphragm 14. For example, a displacement of fluid under the control of the solenoid actuator 26x, as indicated, will be directly related to the diaphragm travel distance and its displaceable area, and, equal to one half the fluid displacement under the control of actuator 26y, and one quarter the fluid displacement under the control of actuator 26z. Similar relationships exist also where actuators 26a, 26b, 26c, of the respective first and second envelopments 10 and 11 are concerned.

Although I have chosen to illustrate the use of diaphragm-like members 14 as fluid displacement members, which are secured to the main body 12 of the envelopments 10 and 11 adjacent the peripheries thereof, it should, of course, be understood that the invention is not to be limited to the use of diaphragm-like members. Piston-like members, for example, being closely fitted within adjacent cylinders may be utilized without de-

parting from the fluid displacement function establishment principles of the invention.

The light source 54, the beam forming member 56, the lens system 60, and the beam receiving means 58 have been arranged in the particular manner as illustrated in the drawing only for the purpose of showing at least one means by which the light beam selection, selection-compensation, and recording-position functions provided by the invention may be utilized. There are numerous other such means of utilizing the function conversion principles 10 of the invention which will become apparent to those skilled in the arts.

Although I have indicated the reflecting surface dimensions of the mirror 43 as being designed to be just slightly greater than the height and width of the largest letter 15 to be received whereby such surface dimensions will permit the mirror 43 to function as a limiting aperture, it will of course be equally understood that a limiting aperture may be supported immediately in front of, or on the 20 surface of, the mirror 43 and thereby perform the same function.

Although I have limited myself, in the illustrations, to the showing of but three binary code related fluid displacement means for light beam selection and selection-compensation functions, and but three binary code related 25 fluid displacement functions where light beam recording-positions are concerned, it should be understood by those skilled in the arts that the invention is not to be limited in this regard. It should also be understood that many of the other embodiments embracing the general principles and constructions hereinbefore set forth, may be utilized and still be within the limits of the present invention.

The particular embodiment of the invention illustrated and described herein is illustrative only, and the invention includes such other modifications and equivalents as may readily appear to those skilled in the arts, and within the scope of the appended claims.

I claim:

1. A hydraulic fluid displacement mechanism for converting binary code related input functions to a light beam selection function and a light beam recording-position function comprising:

- (a) space within first and second hermetically sealed 40 envelopes;
- (b) means for hermetically sealing a fixed amount of fluid within said space of each envelopment and maintaining said fluid in a first static condition;
- (c) fluid sealing means of each of said envelopments including a set of binary code related hermetic fluid displacement members and a hermetic fluid displacement responsive member;
- (d) means for applying binary code related input functions to the fluid displacement members of said envelopments;
- (e) means for deriving first and second fluid displacements, respectively, from said first and second envelopments and changing the respective conditions of said fluid from first static conditions to second static conditions proportional to the value of said binary code related input functions; and
- (f) means for imparting said first and second fluid displacements to the fluid displacement-responsive members, respectively, of said first and second envelopments.

2. A hydraulic fluid displacement mechanism for converting binary code related information to light beam selection and light beam recording-position functions comprising:

- (a) space within first and second hermetically sealed 70 envelopes;
- (b) means for hermetically sealing a fixed amount of fluid within said space of each envelopment and maintaining said fluid in a first static condition;
- (c) fluid sealing means of each of said envelopments 75

including a set of binary code related hermetic fluid displacement means and a hermetic displacement-responsive member;

- (d) first and second sets of binary code information;
- (e) means for applying input functions to predetermine fluid displacement means of said first and second envelopments in response to said first set of binary code information;
- (f) means for applying input functions to predetermined fluid displacement means of said second envelopment in response to said second set of binary code information;
- (g) means for deriving first and second envelopment fluid displacements substantially proportional to the value of said input functions of said first set of binary code information;
- (h) means for deriving second envelopment fluid displacements substantially proportional to the value of said input functions of said second set of binary code information;
- (i) means for changing the respective conditions of said fluid from said first static conditions to second static conditions and imparting said first and second envelopment fluid displacements to the fluid displacement-responsive members, respectively, of said first and second envelopments.

3. A hydraulic fluid displacement mechanism for converting binary code related input functions to light beam selection and light beam recording-position functions comprising:

- (a) first and second hermetically sealed envelopes;
- (b) means for hermetically sealing a fixed amount of fluid within each of said envelopes and maintaining said fluid in respective first static conditions;
- (c) said envelopes including a plurality of hermetic diaphragms;
- (d) means for applying binary code related input functions to predetermined diaphragms of each envelopment;
- (e) fluid displacement means for changing the respective conditions of said fluid from said first static conditions to second static conditions and converting said input functions, respectively, to first and second decimalized functions; and

- (f) means for imparting said first and second decimalized functions to first and second diaphragms, respectively, of said first and second envelopes.

4. A hydraulic fluid displacement mechanism for converting binary code related input functions to light beam selection and light beam recording-position functions comprising:

- (a) first and second hermetically sealed envelopes;
- (b) means for hermetically sealing a fixed amount of fluid within each of said envelopes and maintaining said fluid in respective first static conditions;
- (c) said envelopes including a plurality of hermetic diaphragms for changing the static conditions of said fluid from said first static conditions to predetermined second static conditions;
- (d) means for applying a first set of binary code related functions to predetermined hermetic diaphragms of said first and second envelopes;
- (e) means for applying a second set of binary code related functions to predetermined hermetic diaphragms of said second envelopment;
- (f) fluid displacement means for converting said first set of binary code related functions to first and second decimalized functions and imparting said decimalized functions to first and second diaphragms, respectively, of said first and second envelopes upon changing the first static conditions of said fluid to predetermined second static conditions;
- (g) fluid displacement means for converting said second set of binary code related functions to a third decimalized function and combining said third

7 decimalized function with said second decimalized function for impartation to said second diaphragm upon changing the first static condition of said fluid to said predetermined second static condition.

5. A hydraulic fluid displacement mechanism for converting binary code related input functions to light beam selection, selection-compensation, and light beam recording-position functions comprising:

- (a) first and second hermetically sealed envelopes;
- (b) means for permanently sealing a fixed amount of fluid within each of said envelopes and maintaining said fluid in respective first static conditions;
- (c) said envelopes including a plurality of hermetic diaphragms for changing the static condition of said fluid while preventing the passage of fluid therethrough;
- (d) means for applying a first set of binary code related functions to predetermined hermetic diaphragms of said first and second envelopes;
- (e) means for applying a second set of binary code related functions to predetermined hermetic diaphragms of said second envelope;
- (f) fluid displacement means for converting said first set of binary code related functions to first and second decimalized functions and imparting said decimalized functions to first and second hermetic diaphragms, respectively, of said first and second envelopes;
- (g) means for deriving a light beam selection function from said first diaphragm substantially proportional to said first set of binary code related functions;
- (h) means for deriving a selection-compensation function from said second diaphragm substantially proportional to said first set of binary code related functions;
- (i) fluid displacement means for converting said second set of binary code related functions to a third decimalized function and imparting said third decimalized function to said second diaphragm; and
- (j) means for deriving a light beam recording-position function from said second diaphragm substantially proportional to said second set of binary code related functions.

6. A hydraulic fluid displacement mechanism for converting binary code related input functions to light beam selection and light beam recording-positions comprising:

- (a) first and second hermetically sealed envelopes;
- (b) said envelopes including a plurality of hermetic diaphragms for providing a permanently sealed envelope;
- (c) a fixed amount of hydraulic fluid filling the space within said envelopes to thereby interconnect said diaphragms, respectively, of said first and second envelopes;
- (d) means for applying binary code related functions to predetermined diaphragms of said first and second envelopes for changing said fluid from a primary static condition to a secondary static condition simultaneously with the application of said functions;
- (e) light reflector means associated with at least one diaphragm of each envelope;
- (f) means for effecting secondary static conditions within said first and second envelopes substantially proportional to said binary code related functions;
- (g) said light reflector means being associated with a diaphragm of said first envelope adapted to receive displacements in response to said fluid displacements from said first envelope;
- (h) said light reflector means being associated with a diaphragm of said second envelope adapted to receive displacements in response to said fluid displacements from said second envelope; and
- (i) means for deriving light beam selection functions and light beam recording-position functions from

8 said light reflector means substantially proportional to said binary code related functions.

7. A hydraulic fluid displacement mechanism for converting binary code related functions to light beam reflector selection functions, selection-compensation functions, and light beam recording-position functions comprising:

- (a) first and second hermetically sealed envelopes;
- (b) said envelopes including a plurality of fluid displacement means and fluid displacement-responsive means for hermetically sealing said envelopes and being incapable of admitting the flow of any fluid therethrough;
- (c) a fixed and permanently sealed amount of hydraulic fluid means within said envelopes adapted to interconnect said displacement means and said displacement-responsive means of the respective envelopes;
- (d) light reflector means adapted to receive angular displacements in response to movements imparted to the displacement-responsive means of the respective envelopes;
- (e) means for applying a first set of binary code related functions to the fluid displacement means of said first envelope and to predetermined fluid displacement means of said second envelope for changing said fluid from a primary static condition to a secondary static condition simultaneously with the application of said functions;
- (f) means for applying a second set of binary code related functions to predetermined fluid displacement means of said second envelope for changing additionally the static condition simultaneously with the application of said second set of functions;
- (g) means for effecting static conditions within said first and second envelopes in proportion to the value of said first set of binary code related functions;
- (h) means for effecting static conditions within said second envelope in proportion to the value of said second set of binary code related functions;
- (i) means for imparting a light beam selection function to the light reflector means of said first envelope and a selection-compensation function to the light reflector means of said second envelope corresponding to the value of said first set of binary code related functions; and
- (j) means for imparting a light beam recording position function to the light reflector means of said second envelope corresponding to the combined value of said first and second sets of binary code related functions.

8. A hydraulic fluid displacement mechanism for converting binary code related input functions to light beam reflector selection functions and light beam reflector recording-position functions comprising:

- (a) first and second hermetically sealed envelopes;
- (b) each of said envelopes including a set of fluid displacement members and a fluid displacement-responsive member for hermetically sealing said envelopes and being incapable of admitting the flow of any fluid therethrough;
- (c) a fixed and permanently sealed amount of hydraulic fluid filling the space within each envelope and made to assume a first static condition;
- (d) reference bearing means associated with each fluid displacement member;
- (e) light reflector means associated with each displacement-responsive member;
- (f) actuator means for applying binary code related input functions to said fluid displacement members;
- (g) means for limiting the displacement of each fluid displacement member in accordance with respective requirements of said binary code related input functions;
- (h) means for effecting second static fluid conditions

substantially proportional to the value of said input functions and simultaneously with the application of said functions;

(i) means for imparting said effect of said second static fluid conditions to said fluid displacement-responsive members; and

(j) means for deriving from said fluid displacement-responsive members light beam reflector selection functions and light beam reflector recording-position functions substantially proportional to said binary code related input functions.

9. A binary code controlled mechanism for deriving therefrom a combination of light beam reflector selection, selection-compensation, and recording-position functions comprising:

(a) first and second hermetically sealed envelopes each containing a fixed amount of fluid permanently sealed therein;

(b) said first envelopment including a first set of hermetic input members and a hermetic output member, each being incapable of admitting the flow of any fluid therethrough;

(c) said second envelopment including second and third sets of hermetic input members and a hermetic output member each being incapable of admitting the flow of any fluid therethrough;

(d) reference bearing means for supporting each of said input members in a zero reference position;

(e) light beam reflector means associated with and thereby under the control of each of said output members;

(f) actuator means for displacing said first and second sets of input members in response to a first set of binary code signals;

(g) actuator means for displacing said third set of input members in response to a second set of binary code signals;

(h) means for limiting the displacement of each input member in proportion to the value of said binary code signals;

(i) means for imparting a displacement to said output member of said first envelopment in response to displacements imparted to said first set of input members;

(j) means for imparting a displacement to said output member of said second envelopment in response to displacements imparted to said second and third sets of input members;

5

15

35

40

45

(k) means for deriving a light beam selection function from the reflector means of said first envelopment; and

(l) means for deriving, selectively, a selection-compensation function and a recording-position function from the reflector means of said second envelopment.

10. A binary code controlled mechanism for deriving therefrom a combination of light beam reflector selection and selection-compensation functions comprising:

(a) first and second hermetically sealed envelopes each containing a fixed amount of fluid permanently sealed therein;

(b) said first envelopment including a first set of hermetic input members and a first hermetic output member each being incapable of admitting the flow of any fluid therethrough;

(c) said second envelopment including a second set of hermetic input members and a second hermetic output member each being incapable of admitting the flow of any fluid therethrough;

(d) reference bearing means for supporting each of said input members in a zero reference position;

(e) light beam reflector means associated with and thereby under the control of each of said output members;

(f) binary code controlled actuator means for imparting displacements to said first set and said second set of input members;

(g) means for limiting the displacement, respectively, of said first and second sets of input members upon the impartation of displacements thereto;

(h) means for imparting displacements, respectively, to said first and second output members upon the impartation of displacements to said first and second sets of input members;

(i) means for deriving a light beam reflector selection function from said first envelopment substantially proportional to the value of said binary code controlled actuator functions; and

(j) means for deriving a light beam reflector selection-compensation function from said second envelopment substantially proportional to the value of said binary code controlled actuator functions.
